VAPOR DIFFUSING DEVICES

William D. Turner, New York, Paul Checkovich, Baldwin, and Anthony J. Shukis, Ozone Park, N. Y., assignors to Airkem, Inc., New York, N. Y., a corporation of New York

Application February 7, 1952, Serial No. 270,358

10

3 Claims. (Cl. 299—24)

This invention relates to vapor diffusing devices embodying a container element and a diffuser unit removably supported in said element and to an improved form of diffuser unit per se. More particularly, the invention relates to diffusing devices of the character described wherein the diffusing unit has apertured wall portions providing for emission of vapors therethrough when the diffuser unit is supported in a standing or hanging position in a manner to expose said apertured wall portions. Still more particularly, the invention relates to devices of the character described wherein apertured walls of the diffuser unit provide a chamber for receiving a solid or essentially solidified vapor emanating material. In further particular the invention relates to devices of the character described wherein a vapor diffusing unit adjustably engages the container element in controlling the extent to which apertured wall portions of the diffuser unit are exposed for emission of vapors therethrough.

The novel features of the invention will be best understood from the following description, when taken together with the accompanying drawing, in which certain embodiments of the invention are disclosed and, in which, separate parts are designated by suitable reference characters in each of the views, and in which:

Fig. 1 is a side elevation of one form of vapor diffuser unit arranged within a container element with part of the structure broken away and in section.

Fig. 2 is a side elevation of a vapor diffuser unit as shown in Fig. 1 removed from the container and in operative position, with part of the structure broken away to indicate a modified arrangement of vapor emanating material.

Fig. 2a is a partial sectional view showing the hook element of Fig. 2 utilized for suspending the vapor diffuser unit from the upper edge of the outer container element.

Fig. 3 is a side elevation of a modified form of construction wherein a diffuser unit telescopically engages a container element and is adjustable relative thereto with part of the structure broken away and in section.

Fig. 4 is a partial view substantially on the line 4—4 of Fig. 3 and showing a modification; and

Fig. 5 is a fragmentary view of the top of the device shown in Fig. 3 in closed position with a cover applied and with part of the structure broken away and in section.

In Fig. 1 of the drawing, there is illustrated a vapor diffusing device 10 comprising a container element 11 having suitable closure means as indicated by the screw cap 12 and a diffuser unit 13 arranged within the container. For shipping and storage purposes, an essentially vapor tight seal should be provided between the container 11 and cap 12, and for this purpose, a suitable gasket 14 may be employed extending over at least the container engaging portion of the cap 12, and if desired, an outer seal strip can be applied to the container and cap as indicated at 15, said seal strip engaging the container and cap either tensionally or by adhesive means.

The diffuser unit 13 comprises an essentially cylindrical side wall portion 16 having a plurality of apertures 17

2

at spaced intervals throughout the height and circumference thereof. The lower end 18 of the diffuser unit includes a bottom closure element 19 which has been indicated in the drawing as a cup-shaped member having an annular flange 20 which is secured to the cylindrical wall portion at the lower end 18 thereof by a waterproof adhesive as indicated at 21, or by other suitable retaining means. The upper end of the unit 13 is closed by a disk 22 fitting within the cylindrical wall 16. The disk 22 may be adhesively secured in place or may be merely frictionally supported in engagement with the cylindrical wall 16.

Arranged within the unit 13 is a vapor emanating material which for purpose of illustration is indicated as an essentially cylindrical body 23 of a vapor emanating gel. It will be understood, however, that any solid or essentially solidified form of vapor emanating material may be employed in the diffuser unit 13. As shown in the drawing, a body of gel 23 is initially arranged in the unit 13 with a slight clearance between the outer surface of the gel and the inner surface of the cylinder wall 16 to provide space for circulation of air around the body of gel 23 and outward through the apertures 17 when the diffuser unit is in use. When a gel is employed as the vapor emanating material, it will be understood that as vaporizable material is emitted and consumed, the body of gel will gradually shrink away from the side walls 16 and top 22 of the unit 13; and when the vaporizable components have been all consumed, the body of gel 23 will have been reduced in size to a small, dry kernel having a height and diameter of only about one-fourth the original height and diameter thereof. This change in the size and form of the body of gel 23 provides an easy means for the user to ascertain to what extent the useful life of the device has been consumed.

The unit 13 is also provided with a hanging or suspending device 24 which, for the purpose of illustration, has been indicated in Figs. 1 and 2 of the drawing as a cord 25 knotted centrally thereof to form a loop 26 retaining a hook 27 which is adapted in the extended position shown in Fig. 2 to engage a suitable support 28. The free ends of the knotted cord 25 are provided with clip elements 29 insertable in diametrically opposed apertures 17 of the unit 13 in retaining the cord against displacement from the container unit.

The container unit 13, shown in Fig. 2 in the detached and suspended position, is similar in all external structure to the unit 13 shown in Fig. 1 and embodies an essentially cylindrical side wall 16 having spaced apertures 17 arranged longitudinally and circumferentially thereof with the lower end of the cylinder 16 being closed by an essentially cup-shaped cap 19 cemented or otherwise secured in place and with the upper end closed by a disk 22. The cutaway portion of Fig. 2, however, indicates a modified form of filling for the unit 13 wherein the cylindrical body of emanating material shown in Fig. 1 is replaced by a granular or particled vapor emanating material 30 which may be in the form of lumps of pumice or other absorbent material impregnated with vaporizable components, or which may even be in the form of a vapor emanating gel broken into random-size lumps or pieces. If the vapor emanating material 30 includes particles of small size, it may be desirable to include a vapor permeable liner 31 adjacent the inner surface of the cylindrical wall 16. The liner 31 has been shown for purpose of illustration as an open-work screen or mesh providing free circulation of air and vapors therethrough.

In Figs. 3 to 5 of the drawing, there is shown a modified form of construction wherein a diffusing unit 32, generally similar to the unit 13 and having an essentially cylindrical, external wall 33 with apertures 34 spaced longitudinally and circumferentially thereof, is supported

in a container 35 having an inner surface 36 of essentially cylindrical contour frictionally engaging the outer surface of the unit 32. The frictional engagement between the container 35 and the unit 32 permits extension of the unit 32 to expose one, two, three or more rows of apertures 34 and to provide supporting engagement between the container 35 and unit 32 in such various positions of adjustment. Thus, for example, the complete device with the container 35 and diffuser unit 32 in an extended position, as shown in Fig. 3, may be suspended by the hanger unit 37, comprising looped cord 38 and hook 39 from a suitable support 40. Alternatively, the device with the diffuser unit 32 in suitably extended position can be mounted on a horizontal support 41, in which event the hanger unit 37 will collapse and rest upon the top of the unit 32.

The partial showing in Fig. 4, substantially along the line 4-4 of Fig. 3, indicates the cylindrical wall 33 of the unit 32 as having an inwardly offset portion 42 forming a recess in the outer surface of said cylinder to receive the hanging cord 38. This offset or recess can be preformed in the cylindrical wall, or alternatively may be formed by the action of initially inserting the unit 32 into the container 35 with portions of the hanger cord 38 overlying outer surfaces of the unit 32, as seen in Fig. 3.

The fragmentary view shown in Fig. 4 also indicates a modified construction wherein the top disk 43 of the unit 32 is provided with a plurality of apertures 44 permitting emission of vapors through the top of the unit 32, as well as through the apertured cylindrical wall thereof. It will be understood in this connection that the apertured disk 43 can be used in place of the imperforated disk 22 shown in Fig. 1. It will be further understood that the unit 32, as shown in Fig. 3, can include a top disk or closure of either perforated or imperforated form.

Fig. 5 is a fragmentary view of the top portion of the assemblage shown in Fig. 3 with the container 35 and diffuser unit 32 thereof in collapsed or inoperative position and with the hanger unit 37 collapsed and resting upon the unit 32. The container 35 may be provided with any suitable closure means, and for purpose of illustration, a cap 45 has been shown having a depending flange 46 adapted to overlie a bead or lip 47 protruding outwardly of the top of the container 35. Suitable sealing means is also provided as indicated by the annular gasket ring 48 within the flange 46 for forming a substantially vapor tight seal between the cap 45 and container 35. It will be understood that the showing in Fig. 5 of the drawing is intended primarily to show the general relationship of parts in the collapsed or inoperative position and is not intended to limit the device to any particular closure means or any particular means for mounting the closure on the container 35. The important factor to consider in this connection is that a suitable closure means is one that will provide an essentially vapor tight seal for the container during periods of shipment and storage.

The device, in accordance with my invention, can be employed or utilized in many different ways and for the dispensing or diffusing of vapors of different types and kinds. Thus, for example, the diffuser unit can be employed for the freshening and deodorizing of small confined spaces, such as, closets, garment bags, hampers, or the like or can be used to treat or condition the air of entire rooms. It is to be understood, moreover, that the diffuser unit can contain volatilizable materials of different types and kinds, such as air freshening or deodorizing components, insecticidal and insect repellent agents, fumigants and the like.

The size of the diffuser unit can be varied to meet the needs of the intended use as can the number and arrangement of apertures in the walls thereof. In this connection it should be noted that the rate of diffusion of

vapors from the diffuser unit depends partly upon the number and arrangement of holes or apertures and partly upon the size of the apertures. As shown in the drawing, the diffuser unit has been indicated as having an arrangement of apertures which provides openings having an area equivalent to approximately five per cent of the cylindrical wall area indicating a device intended to have a relatively long effective life, i. e., a slow rate of diffusion of vapors through the apertured walls. When the same free or open space is provided by a smaller number of holes of larger, individual size, the rate of diffusion of vapors is increased to some extent since larger holes offers less resistance to the passage of air and vapors therethrough. For most uses of the device, the number and size of the apertures in the walls of the diffuser unit will be such as to provide an open area equivalent to as little as two to four per cent of the cylindrical wall area when slow volatilization is desired, or as much as 15 to 20 per cent of the cylindrical wall area when rapid volatilization is desired. It should be understood, however, that this range is given merely for illustrative purposes, and in some instances, it may be desirable to employ diffuser units wherein the percentage of open area in a cylindrical wall falls outside this range.

Variations in the rate of volatilization of material from the diffuser unit which can be effected by the telescoping engagement between the diffuser unit and container, as shown in Fig. 3, can also be provided with an assemblage of the type shown in Figs. 1 and 2 by employing suitable suspending means engaging the diffuser unit and the top of the container. By way of illustration, the hook 27, as shown in Fig. 2 of the drawing, can be provided at the cord engaging end thereof with a projecting portion 27'. By inserting the projecting portion 27' in one of the apertures 17 of the diffuser unit and engaging the hook 27 with the upper edge of the container 11, as seen in Fig. 2a, the diffuser unit may be supported in different positions of vertical adjustment with respect to the container. In this connection, it will be noted that the hook 27 can be employed in the manner just described, while remaining in engagement with the cord loop 26. It is within the purview of our invention to employ any type of link or clip means engaging both the container and the apertured walls of the diffuser unit to support the latter in different positions of vertical adjustment.

The diffuser unit can be constructed of any suitable materials which are relatively inert to the particular vaporizable material to be dispensed therefrom. Thus, for example, the diffuser unit can be fashioned from certain metals or plastics or, when producing an inexpensive disposable unit, can be fashioned of suitably treated paper and cardboard.

It is also within the purview of our invention to treat the diffuser unit, as shown for example in Fig. 2, as a distinct article of manufacture and sale apart from the container, in which event the diffuser unit may be wrapped or packaged in accordance with known methods, as for example by wrapping with plastic coated or other essentially vapor impermeable sheeting and closing the wrapping by heat sealing or suitable adhesive means.

Various changes and modifications in the vapor diffusing devices as hereinabove described will occur to those skilled in the art, and to the extent that such changes and modifications fall within the purview of the appended claims, it is to be understood that they constitute part of our invention.

Having fully described our invention, what we claim as new and desire to secure by Letters Patent is:

1. A vapor diffusing device of the character described comprising in combination a container element having essentially vapor-proof closure means therefor, and a diffuser unit removably supported in said element, said diffuser unit comprising a unitary side wall part and top and bottom walls defining a chamber for reception of vapor emanating material, said side wall part having a

plurality of apertures therein providing for circulation of air and vapors through said unit, means operatively engaging at least one of the apertures of said unit whereby said unit can be supported in positions at least partially removed from the container, said last named means comprising an elongated suspending strand having means intermediate the ends thereof supporting a suspending hook, the ends of said strand terminating in clip elements securing said ends of the strand to the apertured walls of the unit, and the strand engaging portion of said hook having a protruding part insertable in apertures of the wall of said unit in suspending the unit from the top of said container by means of said hook.

2. A vapor diffusing device of the character described comprising in combination a container element having essentially vapor-proof closure means therefor, and a diffuser unit removably supported in said element, said diffuser unit comprising a unitary side wall part and top and bottom walls defining a chamber for reception of vapor emanating material, said side wall part having a plurality of apertures therein providing for circulation of air and vapors through said unit, means operatively engaging at least one of the apertures of said unit whereby said unit can be supported in positions at least partially removed from the container, said last named means comprising a suspending element having protruding means adapted to engage at least one of the apertures in the wall of said unit, and other protruding means adapted

5

to engage the upper peripheral edge of said container.

3. A vapor diffusing device of the character described comprising in combination a container element having essentially vapor-proof closure means therefor, and a diffuser unit removably supported in said element, said diffuser unit comprising a unitary side wall part and top and bottom walls defining a chamber for reception of vapor emanating material, said side wall part having a plurality of apertures therein providing for circulation of air and vapors through said unit, and means operatively engaging at least one of the apertures of said unit whereby said unit can be supported in positions at least partially removed from the container, said last named means comprising a flexible suspending device engaging the apertured walls of said container at diametrically opposed portions thereof and including a hook element for mounting on a suitable support, and the diffuser unit having telescoping frictional engagement with said container element.
